PROCESS FOR TREATMENT OF HYDRO-CARBONS

Walter A. Schulze, Bartlesville, Okla., assignor to
 Phillips Petroleum Company, Bartlesville,
 Okla., a corporation of Delaware

Application May 16, 1935, Serial No. 21,903

3 Claims. (Cl. 196—27)

This invention relates to a process of treating hydrocarbons and relates particularly to desulfurization of hydrocarbon oils, particularly petroleum, shale oil and other mineral oils, and 5 more particularly their products.

An object of this invention is to provide a method for treating hydrocarbon oil containing undesirable sulfur compounds comprising a series of desulfurization steps designed to greatly 10 reduce the sulfur content of the hydrocarbon oil.

A principal object of this invention is to provide an improved method for desulfurization of hydrocarbon oil comprising a series of desulfurization steps in which each step is designed to remove a particular type or group of sulfur 15 compounds.

There are various types of sulfur compounds present in the mixtures of hydrocarbons comprising petroleum, coal tar, shale oil and the like.

20 These types of sulfur compounds may be generally classified as (1) the aliphatic and aromatic mercaptans, sulfides and disulfides, which for the sake of brevity are termed non-heterocyclic sulfur compounds, and (2) heterocyclic sulfur compounds, such as thiophenes and thionaphthalenes. Carbon disulfide can hardly be placed in either group since it more or less falls in between the two classes.

I have found that a more complete removal of 25 sulfur from hydrocarbon mixtures containing these various classes of compounds can be obtained by applying a different method of treatment to each of these general classes, rather than to attempt to remove or decompose all of the 30 classes with a single treatment. In other words, a series of treatments each designed to remove a particular group of sulfur compounds from the oil is much preferred to a single treatment as heretofore proposed.

35 The aliphatic and aromatic mercaptans, sulfides and disulfides may be removed from hydrocarbon mixtures by decomposition of these sulfur compounds to hydrogen sulfide and the corresponding olefinic hydrocarbons under conditions such that there is no substantial decomposition 40 of the hydrocarbon constituents of the mixture as described in co-pending application, Serial No. 632,608, filed September 10, 1932, of A. E. Buell and W. A. Schulze entitled "Catalytic process for 45 desulphurization of petroleum vapors". Carbon disulfide, also, is partially removed by such treatment.

The heterocyclic or thiophene type of sulfur 50 compounds is not substantially affected under the 55 conditions applicable to the compounds wherein

the sulfur is not in the ring and a more rigorous treatment which may effect a partial decomposition of hydrocarbon constituents of the mixture is required in this next step.

It has been found that in effecting decomposition of the heterocyclic type of sulfur compound the presence of appreciable quantities of hydrogen sulfide or other sulfur compounds greatly retards the decomposition of the heterocyclic sulfur compounds and, therefore, prevents the re- 5

moval of such sulfur. It is, therefore, particularly advantageous to first treat the hydrocarbon mixture so as to decompose the aliphatic and aromatic mercaptans, sulfides and disulfides and 10

then remove the hydrogen sulfide from the hydrocarbons before treating for the removal of the 15 heterocyclic sulfur. The method I have found best for decomposing the aliphatic and aromatic mercaptans, sulfides and disulfides in a hydro- 20

carbon mixture to hydrogen sulfide comprises passing the mixture in the vapor phase at temperatures above 600° F. over a contact catalyst of the clay type, such as bauxite or fuller's earth or the like, or some other catalyst such as the 25

oxides of chromium, vanadium, molybdenum, tungsten, cadmium and zinc. The preferred 30 temperature range for this step is generally between 600° F. and 800° F. with a treating time factor sufficiently short to avoid substantial de- 35

composition of the hydrocarbon constituents of the mixture. The hydrogen sulfide formed may then be removed from the treated vapors in a conventional manner such as by fractionation or by washing with water, alkali, or other chemical 40 reagent generally used for this purpose. This removal may be done without appreciable cooling of the vapors, if desired, by absorption of the hydrogen sulfide in active oxide absorbents.

In my process these heterocyclic sulfur com- 45 pounds after removal of the other sulfur may be decomposed in either of two ways. Firstly, they may be decomposed in the absence of catalysts by subjecting the hydrocarbon mixture containing them to temperatures at which there is also appreciable decomposition of the hydrocarbon constituents of the mixture. The temperature range is generally above 750° F. and may be as high as 1100° F. depending upon the time factor used and the type of hydrocarbons being treated. 50 This thermal decomposition may be conducted in any conventional apparatus suitable for thermally converting hydrocarbons and it may be treated in the vapor phase, the liquid phase or in the vapor-liquid phase, all such processes being 55

well known and understood by those skilled in the art.

Secondly, these heterocyclic sulfur compounds may be decomposed by treatment in the presence of active catalysts of the metal, metallic oxide and sulfide type such as iron, nickel, cobalt, etc., and the oxides and sulfides of copper, chromium, vanadium, molybdenum, tungsten, cadmium and zinc or mixtures of these oxides and/or sulfides either with or without promoters. In this method the temperature of treatment is lower than that needed in the absence of catalysts, and hence the treatment may be accomplished, if desired, without substantial decomposition of the hydrocarbon constituents. This treatment may be conducted in any conventional apparatus and preferably is done in the vapor phase, although in certain instances liquid phase or vapor-liquid phase treatment may be desirable.

20 It has been noted that in the decomposition of the heterocyclic sulfur compounds according to either of the above described methods most of the sulfur is converted to hydrogen sulfide, although in some instances a part of it may be converted to aliphatic and aromatic mercaptans, sulfides, disulfides, etc. In cases where this organic sulfur is present in appreciable quantities the vapors may again be treated by the method described in the first step, i. e. passage in the 25 vapor phase at temperatures above 600° F. over a contact catalyst of the clay type, such as bauxite or fuller's earth or the like, whereby these organic sulfur compounds are converted to hydrogen sulfide and the latter then removed in any conventional manner.

In a preferred embodiment, therefore, my invention contemplates the treatment of hydrocarbons containing these various types of sulfur compounds by (1) decomposing the aliphatic and aromatic mercaptans, alkyl sulfides and disulfides, (2) removing the hydrogen sulfide from the treated hydrocarbon mixture, (3) decomposing the heterocyclic sulfur compounds, and (4) removing the hydrogen sulfide from the treated 30 hydrocarbons. If in step (3) there results an appreciable amount of sulfur in the form of aliphatic and aromatic mercaptans, sulfides or disulfides, then the hydrocarbon mixture is subjected (prior to step 4) to another treatment as in step 35 (1) to decompose such compounds to hydrogen sulfide.

In the drawing accompanying this application there is shown diagrammatically, one form of apparatus for carrying out my invention.

40 Hydrocarbons are passed through the conduit 10 to an apparatus 11 for decomposition of non-heterocyclic sulfur compounds under the conditions outlined above. The effluents from this decomposition step are passed through the conduit 12 to the separator 13, wherein hydrogen sulfide formed as a result of the decomposition is separated from the effluents which are then passed by means of the conduit 14 to a second decomposition step in apparatus 15, wherein heterocyclic sulfur compounds are decomposed as set forth more fully above. Effluents from the decomposition step are passed to a second separator 16 wherein hydrogen sulfide is separated from the product which is removed by means of conduit 17. 45 In those instances where it is found desirable to separate the lighter hydrocarbons from the heavier hydrocarbons prior to decomposition of the heterocyclic sulfur compounds, the effluents from the apparatus 11 may be diverted to a separator 18 by means of valves 19 and 20. Separator 18

5 may be in the form of a fractionator, or other conventional apparatus capable of separating hydrogen sulfide, lighter hydrocarbons and heavier hydrocarbons. Hydrogen sulfide and lighter hydrocarbons are withdrawn through conduits 21 and 22, respectively, and the heavier hydrocarbons are passed by means of conduit 23 to a second decomposition apparatus 15 for decomposition of heterocyclic sulfur compounds. Valves 24 and 25 may be employed to effect proper flow.

10 As previously stated, it is sometimes desirable to introduce the effluents from the apparatus 15 to a second apparatus for further decomposition of non-heterocyclic sulfur compounds in which case valve 26 could be closed and valve 27 opened 15 to divert the effluents from the apparatus 15 to the apparatus 28 wherein decomposition of any non-heterocyclic compounds formed in the apparatus 28 under the conditions previously set forth may be accomplished.

20 Effluents from the apparatus 28 are then passed through the conduit 29 and valve 30 to the separator 16, wherein hydrogen sulfide is removed from the product. Valve 31 will, of course, be closed.

25 While I have shown diagrammatically one form of apparatus that may be employed, it will be obvious to those skilled in the art that various modifications in the apparatus shown may be made use of in carrying out my invention. Also 30 heaters, heat exchangers and various controls, all of a conventional nature, may be availed of to bring about conditions previously disclosed for the effectuation of my invention.

35 My invention will be clearly understood from the following specific examples of its application.

A hydrocarbon oil such as mixture of petroleum fractions containing sulfur compounds of both the general classes given above is vaporized and heated to a temperature of 725° F. and the vapors 40 passed through a bed of crushed bauxite maintained substantially at that temperature. The vapors will be passed through the bauxite at a rate of approximately ten barrels (liquid volume) 45 per ton of bauxite per hour. The non-heterocyclic sulfur in the form of aliphatic and aromatic mercaptans, sulfides and disulfides is decomposed by the action of the bauxite into hydrocarbon compounds and hydrogen sulfide and the hydrogen sulfide is then removed from 50 the treated vapors in a conventional manner such as by fractionation or by washing with water, alkali, or other chemical reagent or adsorbent generally used for this purpose.

55 The partially desulfurized hydrocarbon mixture is then subjected to either thermal conversion or catalytic treatment as described above to effect decomposition of the heterocyclic type sulfur compounds to hydrogen sulfide and/or aliphatic 60 and aromatic mercaptans, sulfides and disulfides. The hydrogen sulfide is then removed from the other products of this step by one of the conventional methods referred to above and a hydrocarbon oil of very low sulfur content is obtained.

65 In those cases in which appreciable amounts of mercaptans, sulfides, etc., are formed in the mixture during the heterocyclic sulfur conversion step, the mixture is again subjected to the vapor phase contact treatment with bauxite as previously described to decompose these new sulfur compounds to hydrogen sulfide and hydrocarbon compounds. The hydrogen sulfide will then be removed from the mixture by one of the conventional methods and a final hydrocarbon mixture 70 75

having a very low sulfur content will be the final product of the process.

By the above described process a petroleum oil having an original sulfur content of 0.20 per cent will show a final sulfur content of under 0.05 per cent or a reduction of more than 75 per cent in the original sulfur content.

It is also found, in many cases, that the major portion of the sulfur in the form of aliphatic and aromatic mercaptans, sulfides and disulfides will be concentrated in the lighter portions of a hydrocarbon mixture as, for example, in the gasoline and naphtha fractions of a petroleum crude oil. In such cases, after the initial desulfurization step of passing the total mixture over bauxite or other catalyst mentioned above, it will be found economical and expedient to separate the gasoline and naphtha fractions from the heavier fractions which are usually found to contain the principal portions of the heterocyclic type sulfur compounds, and to then subject only the heavier fractions to the subsequent steps. Following the decomposition of the heterocyclic sulfur compounds contained therein, the heavier fractions may, if necessary, be further desulfurized by the catalytic desulfurization step above described.

Other variations of my invention will be readily apparent to those skilled in the art and I therefore desire to claim all such variations which come within the scope of my new invention as defined by the appended claims.

By the term "non-heterocyclic" sulfur as used in the appended claims I refer particularly to such sulfur compounds as the aliphatic and aromatic mercaptans, sulfides and disulfides, and by the term "heterocyclic" sulfur I refer particularly to such sulfur compounds as the thiophenes and thiophanes.

I claim:

1. An improved method of desulfurizing light hydrocarbons which contain non-heterocyclic and heterocyclic organic sulfur compounds, comprising vaporizing the said hydrocarbons, contacting the said vapors while at a temperature within the range from 600° to 800° F. with a bauxite catalyst for a period of about 2 to 10 seconds, whereby the non-heterocyclic organic sulfur compounds are converted into hydrogen sulfide but without any substantial conversion of the heterocyclic sulfur compounds and the hydrocarbon constituents of the vapors, separating

and removing the resultant hydrogen sulfide from the hydrocarbons, subjecting the hydrogen sulfide-free hydrocarbons to thermal treatment at a temperature within the range of 800° to 1100° F. to decompose the heterocyclic sulfur compounds in said hydrocarbons to hydrogen sulfide, and finally removing the said hydrogen sulfide from the treated hydrocarbons.

2. An improved method of desulfurizing light petroleum oil which contain non-heterocyclic and heterocyclic organic sulfur compounds, comprising vaporizing said petroleum oil, contacting the said vapors while at a temperature within the range from 600° to 800° F. with a catalyst of the clay type for a period of about 2 to 10 seconds, whereby the non-heterocyclic organic sulfur compounds are converted into hydrogen sulfide but without any substantial conversion of the heterocyclic sulfur compounds and the hydrocarbon constituents of the vapors, separating and removing the resultant hydrogen sulfide from the petroleum oil, subjecting the hydrogen sulfide-free petroleum oil to thermal treatment at a temperature within the range of 800° to 1100° F. to decompose the heterocyclic sulfur compounds in said petroleum oil to hydrogen sulfide, and finally removing the said hydrogen sulfide from the treated oil.

3. An improved method of desulfurizing light hydrocarbons which contain non-heterocyclic and heterocyclic organic sulfur compounds, comprising vaporizing the said hydrocarbons, contacting the said vapors while at a temperature within the range from 600° to 800° F. with a desulfurization catalyst of the clay type for a period of about 2 to 10 seconds, whereby the non-heterocyclic organic sulfur compounds are converted into hydrogen sulfide but without any substantial conversion of the heterocyclic sulfur compounds and the hydrocarbon constituents of the vapors, separating and removing the resultant hydrogen sulfide from the hydrocarbons, contacting the hydrogen sulfide-free hydrocarbons with a desulfurization catalyst of the metallic oxide type at a reaction temperature, whereby the heterocyclic sulfur compounds are decomposed without any substantial decomposition of the hydrocarbon constituents, and finally removing the said decomposed sulfur compounds from the treated hydrocarbons.

WALTER A. SCHULZE.
